ELECTROMAGNET UNIT

Jerome R. Singer, Berkeley, Calif., assignor to Alpha
Scientific Laboratories, Inc., Berkeley, Calif., a corpora-
tion of California

Filed July 13, 1966, Ser. No. 3,068

Term of patent 14 years

(Cl. D26—1)

FIG. 1

FIG. 2

FIG. 4

FIG. 5

FIGURE 1 is a plan view of the electromagnet unit.
 FIGURE 2 is an end elevational view of the electromagnet unit.

FIGURE 3 is an end elevational view of the electromagnet unit taken from the opposite end from FIGURE 2.

FIGURE 4 is a front elevational view of the electromagnet unit; and,

FIGURE 5 is a rear elevational view of the electromagnet unit.

I claim:

The ornamental design for an electromagnet unit, as shown.
